UNITED STATES PATENT OFFICE.

JOHN L. PARSONS, OF PULASKI, TENNESSEE.

COMBINATION CAN AND BOTTLE OPENER.

Application filed October 30, 1926. Serial No. 145,158.

The present invention consists of a can opener which is so constructed that the cutting part thereof may be effectually forced through the can body without the aid of auxiliary implements, and then urged, in a facile manner, around the can top to sever the latter from the body of the can.

An object of the invention is to provide a can opener embodying handles which operate to force a cutting element into the can, the construction of the opener being such that a relatively light force only is necessary in order to actuate the opener.

Other objects of the invention will be apparent from the following description of the present preferred form of the invention taken in connection with the accompanying drawings wherein:

Fig. 1 is a vertical sectional view of a can opener constructed in accordance with the present invention illustrating the application thereof.

Fig. 2 is a sectional view taken on the line 2—2 of Fig. 1 showing one of the handles with its associate parts in side elevation; and

Fig. 3 is a detail fragmentary perspective view of the opener showing the parts thereof separated to disclose details.

In order to illustrate the application of the present invention a portion of a can 4 is illustrated which is of standard design. As is customary, the top of the can depends into the body and a peripheral bead 5 is provided by the jointure of the can top with the body of the can, in a manner well known in the art.

The opener made in accordance with the present invention embodies handles 6 and 7 each of which is preferably made of metal. The handle 6 has one end thereof enlarged to provide a head 8 the free terminal of which has a portion thereof bent inwardly at right angles to provide a guide flange 9 which is adapted to impinge against the inner wall of the bead 5. By preference the inner wall of the flange 9 is arcuate to permit a lateral oscillatory movement of the handles, during the cutting operation, in a manner more fully hereinafter set forth. The sides of the head 8 are bent inwardly at right angles to provide parallel guides 10 each of which has a portion thereof extended, approximately midway its ends, to provide an ear 11 which is apertured as indicated at 12. Portions of the guides 10

are bent inwardly so as to lie parallel with the body of the head 8 and provide guide fingers 13. The upper end of the handle 6 has the margins thereof folded inwardly to provide a substantially semi-cylindrical structure the terminal of which has an opening 14 formed therein. The handle 7 has the lower end thereof enlarged and the margins of the enlargement bent inwardly at right angles to provide ears 15 which are pivotally engaged through the medium of a pin 16, with the ears 11 of the handle 6. The pin 16 extends through the ears 15 near the body of the handle 7 and also extends through the apertures 12 of the ears 11. Each of the ears 15 has a lug extended outwardly from its margin, as indicated at 17.

Fixedly mounted in the head 8 of the handle 6 is a spacer plate 18 one end of which terminates short of the terminal guide flange 9, the outer face of the plate being spaced from the inner faces of the fingers 13. The space between the plate 18 and the flange 9 is sufficient to accommodate the bead 5 of the can 4, and when the opener is so positioned with respect to the can, the other face of the plate 18 is in horizontal alignment with the inner periphery of the can body. Slidably mounted between the plate 18 and the fingers 13 is a cutting member or blade 19 one end of which is cut obliquely and beveled to provide a cutting edge 20. The opposite end of the blade extends upwardly toward the body of the handle 6 and is provided with an aperture 21 which receives one end of a coil spring 22, the opposite end of said spring being engaged in the aperture 14 of the handle 6. As is apparent from Figs. 1 and 2 of the drawings, the spring 22 normally holds the cutting member 19 in a retracted position in the handle 6. The cutting member 19 is provided in the lateral margins thereof with recesses 23 which are adapted to receive the lugs 17 formed on the ears 15 of the handle 7. Consequently when the handle 7 is urged toward the handle 6 the cutting member 19 is urged downwardly against the resistance of the spring 22. By making the working edge of the cutting member 19 oblique it will be appreciated that an entering point 24 is provided, at the extreme outer end of the cutting member, which first penetrates the can body when the cutting member is actuated. Continued pressure on the handle 7 causes the cutting edge 20 of the cutting

member 19 to bite into the can body in a shear-like manner so as to incise the can top from the can body. When the cutting member 19 has been forced outwardly to its fullest extent, the trailing point 25 of the cutting edge 20 remains within the confines of the head 8 permitting the opener to be continuously urged around the can during the cutting operation eliminating the possibility of impingement of one side of the cutting member in the bight formed between that portion of the can top which has been incised and the can body.

From the above it is believed to be apparent that the user of the opener can completely or partially sever the can top from the can body in a continuous operation by working the handle 7 toward the handle 6 in a shear-like fashion. The cutting member 19 is relatively heavy so as to be urged with facility through the relatively thin can body by the compressive action of the handles. As soon as pressure is released from the handles the handle 7 is automatically moved away from the handle 6 and concurrently the cutting member 19 is retracted in the head of the handle 6. The opener is adapted for use with cans of any size without any adjustment whatsoever.

30 It will be noted that the head 8 of the handle 6 is bent inwardly toward the handle 7 to provide a sloping wall 26 at the jointure of the handle 6 and head 8 which is adapted for the reception of a bottle opener 27. It is apparent that in use of the opener the bill of the opener hook is engaged beneath the bottle cap and the cap removed by a fulcrum movement in a manner well known in the art.

40 Although I have above described the preferred form of my invention it is nevertheless to be understood that various changes may be made therein within the scope of the claims hereto appended.

45 What I claim is:—

1. A can opener consisting of coacting handles one of which is equipped with a can bead embracing terminal, a cutting element slidably mounted in said handle, the other of said handles being engaged with the

5 cutting element to operate the latter when the handles are moved together, and means to automatically urge the handles apart and actuate the cutting member into an inoperative position when pressure on the handles is released.

2. A can opener including a pair of pivotally connected handles, one of which is equipped with a can bead embracing flange, a cutting member slidably mounted in one 60 of the handles and having the cutting edge thereof movable beyond one terminal of the handle, and means mounted on the other handle to engage the cutting member for actuating the latter.

65 3. A can opener including a pair of coacting handles one of which is equipped with a guide flange for impingement beneath the bead of a can, a cutting member slidably mounted in said handle and operable into 70 position beyond said flange for incising the can top, and extensions formed on the other handle for engagement with the cutting member to actuate the latter by relative movement of said handles.

75 4. A can opener including a pair of pivotally connected handles one of which is provided with an arcuate guide flange for engagement beneath the bead of a can, a cutting member slidably mounted in said handle 80 and movable to project a part of the cutting edge thereof beyond said flange, means to normally hold said cutting member in a retracted position in the handle, and means formed on the other handle and cooperable 85 with said cutting member to operate the latter against the resistance of the cutting member retracting means.

5. A can opener including a handle equipped with a guide flange engageable 90 with the inner periphery of the can bead, a cutter element mounted in said handle, and a second handle engaged with the first handle and cooperable with the cutter element to urge the latter through the can body 95 beneath the bead when the handles are moved together.

In testimony whereof I affix my signature.

JOHN L. PARSONS.
